Specification for Design.

Patented May 2, 1922.

Application filed June 10, 1921. Serial No. 476,575. Term of patent 7 years.

To all whom it may concern:

Be it known that we, ALFRED A. GLIDDEN and ELUE O. FRITCH, citizens of the United States, residing at Watertown and Belmont, respectively, in the county of Middlesex and Commonwealth of Massachusetts, have invented a new, original, and ornamental Design for a Vehicle Tire, of which the following is a specification, reference being had to the accompanying drawing, forming part thereof.

In this drawing Fig. 1 is a developed plan view of a sufficient portion of a tire to illustrate our new design.

Fig. 2 is a side elevation, and

Fig. 3 a transverse section on line 3, 3 of Fig. 2.

We claim:

The ornamental design for a vehicle tire as shown.

ALFRED A. GLIDDEN.
